DFS. 2210

Alonzo B. Bailey, of Middle Haddam, Conn.

Letters Patent No. 2210-Dated Octr 31-1865

Design for a Coffin Handle.

The schedule referred to in these Letters Patent and making part of the same.

To all whom it may concern:

Be it known that I, Alonzo B. Bailey, of Middle Haddam, in the County of Middlesex and State of Connecticut, have invented a new and original design for Coffin Handles; and I do hereby declare that the following is a full, clear and exact description thereof which will enable those skilled in the art to make and use the same, reference being had to the accompanying drawing, which forms a part of this specification.

The drawing fully represents the design.

The ears A are made with the outline represented. The outer edge of the upper surface of said ears A is bordered by a continuous row of raised or projecting dots B, but the shoulder from which said dots project is sunk a little below the plane of the burnished portion of the surface of said ears. In the central part of the surface of the ears upon an elliptical ground work C, of parallel horizontal lines are raised figures; that is to say, in the part of said ellipse C, which is nearest to the handle D, is the raised figure of an altar or desk E, the front of which is ornamented with a curtain F, looped up in three festoons. Three tassels depending from each point at which the curtain is looped up. Upon the lower inclined part of said altar or desk appear in raised letters the words "in memory of." Upon the desk is laid an open book showing in raised letters on the left hand page the word "Holy" and on the right hand page the word "Bible." In the end of the altar or desk E, next to the handle D, is made an opening for the reception of that part of the handle D, which forms the hinge or pivot. Immediately above the desk and book is seen a rising sun with diverging rays, about

one half the disc, being seen above the open book. At the end of the altar or desk farthest from the handle, stands an angel C, with drooping wings looking towards the desk. The angel has the hand next to the beholder resting upon the upper edge of the desk near its front, the hand farthest from the beholder being raised and pointing upward. Beneath the wings of the angel is seen a spire and part of the building of a church H. The ears A are attached to the coffin by screws in the usual manner. The handle D has the usual form, and is pivoted to the ears A in the usual manner, but upon that part of the handle D, which is grasped by the hand in carrying the coffin is seen a flying angel in relief, upon an elliptical groundwork of parallel lines. The angel is surrounded by scroll work K, consisting of leaves, birds and flowers as represented in the drawings.

I claim as new and desire to secure by letter Patent the design or pattern for coffin handles herein set forth.
